UNITED STATES PATENT OFFICE

WILLIAM E. MORTRUDE, JR., OF SEATTLE, WASHINGTON

DESIGN FOR AN ELECTRICAL TREATMENT CABINET

Application filed June 20, 1932. Serial No. 44,137. Term of patent 14 years.

To all whom it may concern:

Be it known that I, WILLIAM E. MORTRUDE, JR., citizen of the United States, residing at Seattle, in the county of King and State of Washington, have invented a new, original, and ornamental Design for Electrical Treatment Cabinets, of which the following is a specification, reference being had to the accompanying drawing, forming part thereof, and wherein—

Figure 1 is a view in side elevation of an electrical treatment cabinet, showing my

new design; Fig. 2 is a view in front end elevation of the same; and Fig. 3 is a view in rear end elevation.

The side not shown in the drawing is the same as the side shown in Figure 1 of the drawing.

I claim:

The ornamental design for an electrical treatment cabinet, as shown and described.

In testimony whereof I affix my signature.

WILLIAM E. MORTRUDE, JR.
